UNITED STATES PATENT OFFICE.

ROBERT C. STEVENS, OF ERIE, PENNSYLVANIA.

HEATER.

1,102,452.

Specification of Letters Patent.

Patented July 7, 1914.

Application filed April 5, 1912. Serial No. 688,662.

To all whom it may concern:

Be it known that I, ROBERT C. STEVENS, a citizen of the United States, residing at Erie, in the county of Erie and State of Pennsylvania, have invented certain new and useful Improvements in Heaters; and I do hereby declare the following to be a full, clear, and exact description of the invention, such as will enable others skilled in the art to which it appertains to make and use the same.

This invention is a heater and relates more particularly to water heaters of the general class in which water is circulated through the heater while the space surrounding the water is filled with steam, the exhaust from gas engines, or other heating medium, the construction of the heater being such that the water is divided into thin layers and caused to pass a number of times through the length of the heater.

The object of my improvement is to provide a sectional heater that can be made of cast iron, and that shall be capable of being used either as a vertical or horizontal heater without change of construction.

A further object is to so construct the heater sections that they are easy to mold, and of such form as to procure sound castings.

A further object is to so brace the walls of the heating surfaces that the heater will withstand high water pressure.

Another object is to so construct the heater as to obviate the use of heating tubes and of the cover plates heretofore required on the water spaces of cast iron heaters.

The parts are so arranged that very little machine work is required, and the heater is of comparatively light weight for a given heating capacity.

A further object is to so construct the heater that it can be easily enlarged and the capacity thereby increased by adding new sections as required.

My invention also includes a construction of the heads of the heater so that the inlet and outlet steam connections can be easily attached to the heater whether the steam connections of the heater be placed vertically or horizontally.

With these and certain other objects in view which will appear later in the specification, my invention consists in the constructions and devices described and claimed and the equivalents thereof.

In the drawings, Figure 1 is a part sectional elevation of the device arranged as a vertical heater, the reinforcing spools or bars being shown in the middle section but omitted from the upper and lower sections for the sake of clearness; Fig. 2 shows the heater arranged horizontally; Fig. 3 is a top plan view of half of one of the heater sections, the upper part of the view being an enlarged section on the line 3—3 of Fig. 1; Fig. 4 shows the upper face of half of one of the heater sections; Fig. 5 is a view of the inner face of one of the heater ends or heads; Fig. 6 is a section taken on the broken line 6—6 of Fig. 5; Fig. 7 is a section taken on the line 7—7 of Fig. 5; Fig. 8 is a section on the line 8—8 of Fig. 5; Fig. 9 is a view of the inner face of the opposite head; Fig. 10 is a section on the broken line 10—10 of Fig. 9; and Fig. 11 is an exterior view of the head shown in Figs. 9 and 10.

The shell of the heater is formed of one or more removable sections 1. If more than one is used, they are secured together end to end by bolts or otherwise, as shown in Fig. 1. Each of the sections is formed in a single piece, preferably made of cast iron. At the two ends of the assembled sections are secured heads 2, 3. One of these heads as 2 is arranged to form a steam chamber 4 and is provided with a number of water return passages 5. The construction of the same will be explained later. The other head 3 is similarly formed with a steam chamber 6 and water return passages 7 and in addition is provided with water pockets 8 and 9 communicating respectively with the water inlet 18 and outlet 19. The head 2 has a steam inlet 10 and head 3 has a steam outlet 11, or vice versa. Each of the middle sections is preferably formed with a rectangular or other shaped shell 12 having end flanges 13 and each section is divided by a series of parallel partitions 14 extending lengthwise from end to end, into a series of parallel steam passages 15 and water passages 16, the ends of the partitions of each section registering with those of the next adjacent section, to form continuous partitions extending from head to head.

The partitions 14 are preferably stiffened by means of spacing braces 17 preferably cast integral with the partitions and extending across the passages 15 and 16.

To assemble the heater the desired number of sections 1 are arranged end to end

with their respective steam and water openings registering, and the sections are then bolted together, providing parallel series of water and steam passages that extend from 5 end to end of the assembled structure, the steam and water passages alternating. The end sections or heads are then bolted in place. One of these heads 2, which serves as a top head when the heater is to be used 10 as a vertical heater, has its openings so arranged that all of the steam passages 15 lead into its steam chamber, and all of the water passages 16 lead into its water return passages 5. Each of these water passages 15 communicates with two of the water passages 16, as shown in Fig. 1, so that water flowing through one of the water passages 16 will turn in passage 5 and flow through the next succeeding water passage in the opposite 20 direction. The water passage 5 is not in communication with the steam passages. Similarly, the other head, which in the case of a vertical heater may be designated the bottom head 3, has its steam chamber 6 in communication with each of the steam passages 15 and its water return passages 7 are respectively in communication with the water passages 16 of the sections 1, in which the direction of flow is again 30 reversed.

I prefer to make the pocket 5 of less length than the width of passages 15 and 16, so that it extends only part way across the head, as shown in Figs. 7 and 8, therefore 35 by leaving a part of the length of steam passage 15 uncovered to permit free flow of steam from chamber 4 into all of the steam passages. Similarly, pocket 7 is preferably of less length than the passages 15 and 16.

40 In operation, water is admitted to the inlet 18, passes through pocket 8, thence up through the corresponding water passage 16 to the top head where it enters the water return passage 5 and thence travels down 45 through the next water passage 16 into the water return passage 7 of the bottom head, thence upward again to the upper head and down to the lower head. This travel may be repeated as many times as desired, depending 50 upon the number of water passages provided. In the form illustrated I have shown six such passages, so that the water travels the length of the heater six times before it finally enters the water outlet 55 pocket 9 and passes out through the outlet 19.

Steam introduced through the inlet 10 of the top head 2 passes from the steam chamber 4 simultaneously through the steam passages 15 and down to the steam chamber 6 of the head 3, thence through the steam outlet 11. The water of condensation is drawn out through the drain 21, when the heater is in the horizontal position. The 65 openings 18, 19 and 20 are provided for

blowing off sediment, though 18 and 19 serve the additional purpose of water inlet and outlet, as previously described.

While I have for convenience described the passages 15 as "steam" and 16 as "water" passages, it will be understood that the heater is intended to employ any other heating medium, as the exhaust from gas engines and the like; and any other fluid to be heated. It may also be employed as a cooler or condenser.

Having described my invention, what I claim and desire to secure by Letters Patent, is:—

1. In a heater, the combination of a plurality of shell sections, each comprising a plurality of parallel longitudinally disposed partitions extending from side to side thereof, integral with said shell and dividing said shell into alternating steam and water 85 passages; of heads secured to the outer end of the extreme shell sections, each head formed with a steam opening and having a steam chamber, said chamber communicating with each of the steam passages; said head formed with integral water pockets, each of said pockets having one end in communication with one of said water passages, the opposite end of said pocket communicating with the next succeeding water passage; all of said water passages being connected in continuous series, but out of communication with the intermediate steam passages; a water inlet at one end of the series of water passages, a water outlet at the opposite end of said series; said series of passages adapted to conduct water in a thin sheet along the walls of said steam passages from one end to end of the heater, the water being guided alternately in opposite directions, for the purposes set forth.

2. In a heater formed of a plurality of shell-sections arranged end-to-end and heads secured to the extreme sections; each section formed of a single piece of cast metal 110 and comprising a rectangular outer shell and a plurality of flat partitions arranged lengthwise said sections, said partitions being parallel and extending from side to side across said shell and a plurality of transverse spacing braces connecting adjacent partitions and cast integral therewith.

3. In a heater formed of a plurality of shell sections arranged end to end and heads secured to the extreme sections; each section formed of a single piece of cast metal and comprising a rectangular outer shell and a plurality of flat partitions arranged lengthwise said section, said partitions being parallel and extending from side to side 125 across said shell, and a plurality of transverse spacing braces connecting adjacent partitions and cast integral therewith; each of said heads formed with a steam opening and having a steam chamber, the steam 130

chamber of one head communicating directly with the steam chamber of the opposite head through the passages formed between alternate pairs of said parallel partitions; each head formed with a plurality of water pockets, each pocket communicating with the water passage formed between alternate pairs of said parallel partitions, said pockets connecting the water passages 10 in series to form a single conduit to guide

water in a thin sheet along the walls of said steam passages alternately in opposite directions from end to end of the heater, for the purposes set forth.

In testimony whereof, I affix my signature 15 in presence of two witnesses.

ROBERT C. STEVENS.
